UNITED STATES PATENT OFFICE.

JOHN F. CAVANAGH, OF MERIDEN, CONNECTICUT, ASSIGNOR TO CONNECTICUT TELEPHONE & ELECTRIC COMPANY, INC., OF MERIDEN, CONNECTICUT, A CORPORATION OF CONNECTICUT.

SWITCH.

1,249,027.

Specification of Letters Patent.

Patented Dec. 4, 1917.

Application filed October 4, 1916. Serial No. 123,785.

To all whom it may concern:

Be it known that I, JOHN F. CAVANAGH, a citizen of the United States of America, residing at Meriden, New Haven county, Connecticut, have invented a new and useful Switch, of which the following is a specification.

My present invention relates particularly to control switches for automobiles, the general objects of my invention being to provide simple and compact switch mechanism for controlling such devices as the ignition apparatus, lamps and signal mechanism. A special object of the invention is to incorporate the control of these three functions in a single compact device, which may be readily mounted in place and wired up with the respective mechanisms.

Another object is to enable the mounting of the control switch in a convenient and accessible position, and to so construct the device that it may be readily and easily manipulated for the different functions.

In addition to these objects, I aim to provide a switch of the character set forth which will be relatively inexpensive, and which may be readily applied to the machines without the need for any special attachments or fixtures.

In the accomplishment of the foregoing, I construct a switch with a rotatable push button for controlling the lights and horn or other signal element and switch contacts for controlling the ignition circuit, said ignition switch being usually and preferably operated by key mechanism, and the push button being arranged to control the lights by its rotary movements, and the signal device by its push movements.

A special feature of the switch is the provision of it with a screw threaded member in the nature of a nut, adapting the same to be screwed as a single unit on the top of the customary steering column.

Other features of the invention are special arrangements and constructions of the various contacts, the construction and control of the push button and such further features as will appear as the specification proceeds, attention being directed to the accompanying drawings forming part hereof, and wherein I have disclosed a practical commercial embodiment of the invention.

In said drawings:

Figure 1 is a view in side elevation showing the switch applied to the head of a steering column, the latter being indicated only in dotted lines.

Fig. 2 is a top plan view of the switch.

Fig. 3 is a side view of the electrical conducting parts and indicating the supporting housing in dotted lines.

Fig. 4 is a view of the underside of the insulating base which forms the cover of the casing showing the contacts and terminals carried thereby.

Fig. 5 is a plan view of the casing and key operated mechanism controlling the ignition switch.

Fig. 6 is a top plan view of the electrical conducting parts, illustrating diagrammatically the circuit connections and devices controlled.

Fig. 7 is a vertical sectional view of the switch taken substantially on the plane of the line 7—7 of Fig. 2.

The body of the switch illustrated, consists of a casing 10 and a cover 11, said cover being preferably constructed of insulating material to form an insulating base 80 and support for the contacts, and the two forming, as illustrated in Fig. 3, a housing for the several parts.

To enable the attachment of the switch to a steering column, or other desirable support, the bottom of the casing may be formed into a nut, as indicated at 12, screw-threaded to fit the screw threads on the upper end of a steering column, such as that indicated at 13 in Fig. 1.

The contacts for controlling the ignition circuit are designated 14 and 15 and are shown as two strips of metal embedded or seated in slots formed in an insulating supporting portion 16 dependent from the top 11. One of these contacts 14 is shown provided with an angularly extending arm 17 forming a circuit terminal which may be provided with a binding screw or simply a hole 18 to receive the wire, while the other contact strip 15 is shown doubled upon itself to provide a terminal end 19 having a binding screw or similar device 20, said two strips being held in their seats by an overlying washer 21 fastened by a screw 22.

As indicated in Fig. 6, one of these con-

tacts such as the contact 15, is usually connected through suitable circuit connections with a magneto, or other current source 23, and the other contact may be connected with 5 a coil 24, the rest of the ignition circuit being completed, for instance, through suitable distributor mechanism (not shown), and grounded, as indicated at 25.

The circuit through the ignition contacts 10 is preferably controlled by key operated mechanism such as that disclosed in Fig. 5 and consisting of a plunger 26 for forcing the two contacts together, carried by a spring 27 and operated by a key 28, the bit 29 of 15 which may bear directly upon the supporting spring 27. The plunger 26 is shown mounted in a suitable bracket 30 which also provides a mounting for the spring 27 and a seat for the inner end of the key. This 20 bracket may be readily supported in place by bossing it outward into an escutcheon, as indicated at 31, and engaging this bossed out portion in an opening 32 in the side of the casing, this arrangement preventing 25 sidewise shifting of the key mechanism and a lug 33 dependent from the top of the housing engaging in a notch 34 in the upper edge of the bracket to hold the same against movement in other directions. The key may be 30 yieldingly held in the circuit closing position by indenting or grooving the spring 27 as indicated at 27' in Fig. 5, to receive the edge of the bit of the key.

35 designates the push button controller for the lighting and signal circuits, said push button in the illustration having a dependent rim 36 encircling the upstanding circular portion 37 on the insulating base and carrying a segmental contact 38 on the underside thereof for engagement with the several control contacts.

Current is conducted to this segment in the present illustration by a yielding spring contact 39, which forms the first one of three 45 contacts grouped circularly about the axis of the push button; the other two contacts 40 and 41, respectively, constituting the so-called "dim" and "bright" contacts for the lamps.

50 The horn or other signal element is controlled by the engagement of the segmental contact with a contact 42 which, in the present disclosure, forms a center contact and substantially encircles the spindle 43 which 55 forms the pivotal support for the push button. This signal contact is, as shown in Fig. 3, mounted on a plane lower than that of the other contacts, and said other contacts are preferably yielding in their nature and 60 enough higher than the signal contact to support the button segment normally out of engagement with the signal contact.

I have secured this resiliency in the supporting contacts, in the case illustrated, by 65 making said contacts from flat strips of

spring metal folded back and forth upon themselves a number of times, as indicated at 44 to form zig-zag springs, these springs being guided in their vertical yielding movements by the side walls of the relatively 70 deep sockets 45 in which they are seated.

The segment contact 39, which carries current to the button segment, is shown provided with an extension 45' projecting down through the top into electrical engagement 75 with the terminal arm 19 of the ignition contact 15 and the light controlling contacts 40-41 are shown provided with dependent terminal extensions 46 and 47 having suitable binding devices or wire openings 48 80 and 49.

In the construction disclosed the push button is yieldingly supported by the yielding spring contacts with the segment carried thereby normally out of engagement with 85 the signal contact. To sound the signal device therefor, it is merely necessary to depress the button, the current flow in this case being from the segment contact 39 and segment 38 to the signal contact 42 and from 90 the binding post 50 of said signal contact through a conductor 51 to the signal horn 52 and thence to ground. The signal terminal 50 may be connected with the signal contact as by means of a tubular rivet 53 95 passed through the insulating base and serving to secure both said parts in place. The rising movements of the push button may be limited by a stop washer 54 secured to the lower end of the button spindle by a screw 100 55 which thus serves to rotatably confine the spindle to the base and hold the segment carried thereby in engagement with the circularly arranged set of contacts.

The rotary movement of the push button 105 is also preferably limited, as by means of a stop lug 56 (Fig. 2) working in a cut-out 57 in the side of the circular portion of the insulating base and engaging the stop shoulders 58 at opposite ends thereof. Also the 110 push button is preferably yieldingly held in the various positions to which it is turned, as by means of a spring 59 on the side of the base having an outstanding lug 60 to engage in notches 61 on the inside of the dependent 115 rim of the button. This spring may be formed as an integral extension of the center contact angled over the side of the base.

Suitable indications are preferably provided for the different control positions of 120 the push button. Thus in the illustration (Fig. 2) the top of the housing bears the words "Off" "Dim" and "Bright" and the button carries an arrow or similar indicating device 62 which, when alined with the 125 respective indications, produces the results indicated.

In the diagrammatic view, Fig. 6, the button is indicated in the "off" position with the segment turned so that it engages only 130

the current supplying contact 39. If the button is then rotated right handedly to carry it to the "dim" position, then the segment will be in engagement with both the 5 first contact 39 and the second contact 40 which will cause a supply of current to flow through the resistance or other suitable dimming device 63 connected with the second contact, through a conductor 64 to the lights 10 65, this circuit being also completed in the illustration through the common ground. If the button be now rotated into the final "bright" position, the dimming device will be short-circuited by the engagement of the 15 contact segment with the last contact 41 and the current will then flow in full force to the lights.

The many advantages of the invention will be apparent. The advantage of having 20 the entire control for the ignition light and signal embodied in a single conveniently operated device being especially important and the ready adaptability of this device to existing systems being also of considerable importance.

A feature of special importance is the provision of the several contacts with terminals consisting simply of holes punched to receive the ends of the wires. This is a 30 simple manufacturing proposition and this flat form of terminal enables the quick dropping of the contacts down into their seats in the base. The wires can be permanently secured by doubling the ends of the wires 35 through the holes and sealing them with a drop of solder. In practice the wire ends are secured to the insulating base with the wires attached and then applied to the box or casing with the wires extending through 40 the nut in the bottom of the casing and the whole is then ready to be applied to the steering column or other support.

What I claim is:

1. In a switch of the character described, 45 a rotatably supported push button, a segmental contact carried by said push button, a centrally located contact for engagement by said segment, a series of contacts grouped about said center contact and normally engaged by the segmental contact, and means for normally yieldingly supporting the push button with the segmental contact out of engagement with the center contact.

2. In a switch of the character described, 55 a rotatably supported push button, a segmental contact carried by said push button, a centrally located contact for engagement by said segment, and a series of contacts grouped about the center contact and engaging the segmental contact to normally yieldingly support the same out of engagement with the center contact.

3. In a switch of the character described, 65 an insulating base, a center contact on said base, a rotatably supported push button

above said base, a contact on the underside of said push button for engagement with the center contact, and a series of spring contacts disposed about the center contact, and engaging the push button contact to yieldingly support the same out of engagement with the center contact.

4. In a switch of the character described, a rotatable push button, a contact carried by said push button, a set of yielding contacts 75 beneath the push button and adapted to be engaged by the push button contact in the rotation of the push button, and another contact disposed at a lower elevation than the yielding contacts and adapted to be engaged by the push button contact in the push movements of the push button.

5. In a switch of the character described, a substantially circular insulating base, a center contact on said base, yielding side contacts on said base disposed at higher elevations than said center contact, a push button pivotally engaged on the base and provided with a dependent rim encircling the base, and a contact segment on the underside of 90 the push button adapted for engagement with the center and side contacts aforesaid.

6. In a switch of the character described, a substantially circular insulating base, a center contact on said base, yielding side 95 contacts on said base disposed at higher elevations than said center contact, a push button pivotally engaged on the base and provided with a dependent rim encircling the base, a contact segment on the underside of 100 the push button adapted for engagement with the center and side contacts aforesaid, cooperating stops on the base and dependent rim for limiting the rotary movements of the push button, and means for yieldingly 105 holding the push button in the different positions to which it may be rotated.

7. In a switch of the character described, a substantially circular insulating base, a center contact on said base, yielding side contacts on said base disposed at higher elevations than said center contact, a push button pivotally engaged on the base and provided with a dependent rim encircling the base, a contact segment on the underside of the push 115 button adapted for engagement with the center and side contacts aforesaid, and cooperating means on said base and dependent rim including a spring on one of said members engaging in notches in the other of said 120 members for yieldingly holding the push button in the different positions to which it may be rotated.

8. In a switch of the character described, a substantially circular base, contacts on said base, an angular extension on one of said contacts projecting out at the side of the base, a button rotatably engaged on the base and provided with a dependent rim encircling the base and inclosing the exposed 130

portion of said angular extension, said rim having seats to receive the outwardly projecting part of the extension aforesaid, and a contact on the underside of said button for engagement with the contacts on the base.

9. In a switch of the character described, an insulating base, a spindle on said base, a rotatable button on said spindle, a contact on the lower face of said button, a center contact on the base substantially encircling the spindle in the plane of the contact on the lower face of the button so as to be engaged thereby, and contacts on the base grouped about said center contact in position to be also engaged by the contact on the button.

10. In a switch of the character described, the combination of a housing, switch contacts in said housing, key operated means in said housing for closing the circuit through said switch contacts, a center contact on top of the housing, side contacts grouped about said center contact and one of said side contacts being electrically connected with one of the above mentioned contacts in the housing, a push button rotatably mounted on top of the housing, and a segmental contact on the underside of said push button for cooperation with said center contact in the push-button movements of the button and with the side contacts in the rotary movement of the button.

11. In a switch of the character described, a casing, a key operated plunger mounted in said casing, an insulating base closing the top of said casing, co-operating switch contacts carried by said insulating base and including a yielding contact disposed in the plane of the key operated plunger, contacts mounted on top of said insulating base, one of said contacts being electrically connected with one of the switch contacts aforesaid, an operating button rotatably and reciprocably mounted on the insulating base, and a contact carried by said button for engagement with certain of said contacts on the top of the base in the push-button movements of the push-button and with certain other of the contacts in the rotary movement of the button.

12. In a switch of the character described, the combination with ignition contacts provided with ignition circuit terminals, of a rotatably mounted push button, a contact segment carried by said push button, lighting contacts for engagement by said segment provided with lighting circuit terminals, a current supplying contact normally in engagement with the segment and electrically connected with one of the ignition contacts and a signal contact disposed at a lower elevation than said current supplying contact so as to be engaged by said contact segment only when the push-button is depressed.

13. In a switch of the character described,

an insulating base and a push button rotatably confined thereto, a contact carried by said push button, contacts on said base, and means for yieldingly holding the push button in various angular positions on said base comprising a spring carried by one of said members and the other of said members having notches receiving said spring and slidably engaging the spring to permit of the push button movements of said push button.

14. In a switch of the character described, a rotatably supported push button, a contact carried by said push button, a yielding contact beneath the push button and disposed to be engaged by the push button contact in the rotation of said push button and another contact disposed at a relatively lower elevation than the yielding contact in position to be engaged by the push button contact in the push movements of the push button.

15. In a switch of the character described, a rotatable push button, a contact on the underside of said push button, a relatively stationary contact beneath the push button contact in position to be engaged by said push button contact in the push movements of the push button, a yielding contact beneath the push button in position to be engaged by the push button contact in the rotary movements of the push button and normally yieldingly supporting the push button with the contact thereon out of engagement with the first relatively stationary contact and means for yieldingly holding the push button in different positions to which it may be rotated.

16. In a switch of the character described, a rotatable push button, a contact on the underside of said push button, a relatively stationary contact beneath the push button contact in position to be engaged by said push button contact in the push movements of the push button, a yielding contact beneath the push button in position to be engaged by the push button contact in the rotary movements of the push button and normally yieldingly supporting the push button with the contact thereon out of engagement with the first relatively stationary contact.

17. In a switch of the character described, an insulating base, a push button rotatably supported on the insulating base and having a rim portion by which the button may be rotated, a contact on the under side of the push button, a yielding contact on the insulating base within the rim of the push button normally supporting the push button in an upright position and engaged by the push-button contact in the rotary movement of said push-button and a contact on the insulating base within the rim and disposed in position to be engaged by the push

button contact in the push movements of said push button.

18. In a switch of the character described, an insulating supporting base, having a substantially cylindrical portion, a push button having a dependent rim covering the substantially cylindrical portion of the base and providing a finger hold by which the push button may be rotated, a stud rotatably confining the push button on the insulating base, and permitting a limited reciprocating movement of the push button on the base, a spring member on the base engaging the under side of the push button to normally hold the same projected to the extent permitted by the securing means aforesaid, a contact on the under side of the push button and a contact on the base in position to be engaged by the push button contact when said push button is depressed and contacts carried by the base and button adapted to be engaged by the rotary movements of the button on the base.

19. A switch of the character set forth comprising a base, an operating member rotatably confined to said base and capable of push-button movements in respect thereto, a set of push-button contacts brought into engagement by the push-button movements of said operating member, and contact elements engaged by the rotary movement of the operating member independently of said push-button action.

20. A control-switch comprising an insulating base, a rotatable push-button rotatably confined to said base, and capable of bodily push-button movements in respect thereto, a contact on the base, a contact carried by the push-button and brought into engagement with said contact on the base by the push-button movements of said button, means for yieldingly supporting the push-button with said contacts normally separated, a second contact on the base and a contact connected with the push-button and carried thereby in the rotary movements thereof into engagement with the second contact on the base.

21. A switch of the character set forth comprising a base, an operating member rotatably confined to said base and capable of push-button movements in respect thereto, a set of push-button contacts brought into engagement by the push-button movements of said operating member, contact elements engaged by the rotary movements of the operating member independently of said push-button action, means for yieldingly supporting the operating member with said push-button contacts normally disengaged and means for retaining the operating member in the position to which it is rotated.

22. A switch of the character set forth comprising a base, an operating member rotatably confined to said base and capable

of push-button movements in respect thereto, a set of push-button contacts brought into engagement by the push-button movement of said operating member, contact elements engaged by the rotary movement of the operating member independently of said push-button action, and means for limiting the rotary and push-button movements of the operating member on the base.

23. A control switch comprising an insulating base, a rotatable push-button rotatably confined to said base, and capable of bodily push-button movements in respect thereto, a contact on the base, a contact carried by the push-button and brought into engagement with said contact on the base by the push-button movements of said button, means for yieldingly supporting the push-button with said contacts normally separated, a series of contacts on the base and a contact connected with the push-button and carried thereby in the rotary movements thereof into engagement with the contacts of said series.

24. A control switch comprising a base, a rotatable push-button, means for rotatably and reciprocably confining said push-button to the base, a set of contacts adapted to be carried into engagement by the push-button movements of said push button, means for yieldingly supporting the push-button with said contacts normally disengaged and a second set of contacts having one element thereof connected with the push-button and operated thereby in the rotary movements of such push-button.

25. A control switch comprising a base, a push-button having an unobstructed push-button top surface by which the push-button may be depressed, and a finger grip rim by which the button may be rotated, means for rotatably confining the button to the base adapted to permit of a limited movement of the button toward and away from the base, contacts adapted to be forced into engagement by the button in the push button movements thereof, means for yieldingly supporting the button with said contacts normally disengaged, and a set of contacts having an element connected with and operated by the button in the rotary movements thereof.

26. A control switch comprising a base, a push button having an exposed push button top surface and, in addition, means for rotating the button, means for rotatably confining the button to the base adapted to permit of a limited movement of the button toward and away from the base, contacts adapted to be forced into engagement by the button in the push button movements thereof, means for yieldingly supporting the button with said contacts normally disengaged, and a set of contacts having an element connected with and operated by the button in the rotary movements thereof.

27. A control switch comprising a base, a rotatable push-button, means for rotatably and reciprocably confining said push-button to the base, a set of contacts adapted to be carried into engagement by the push-button movements of said push-button, means for yieldingly supporting the push-button with said contacts normally disengaged, a second set of contacts having one element thereof connected with the push-button and operated thereby in the rotary movements of such push-button, and a dependent rim portion on the button substantially inclosing the contacts.
- 10 28. A control switch comprising an insulating base, a rotatable push-button rotatably confined to said base, and capable of bodily push-button movements in respect thereto, a contact on the base, disposed beneath the central portion of the button, a centrally located contact portion on the button for engagement therewith, a radially

projecting contact portion connected with the button and movable therewith in the rotary movements of the button and a contact on the base for engagement by said radially projecting contact portion in the rotary movement of the button. 25

29. A control switch comprising a base, a rotatable push-button, means for rotatably and reciprocably confining said push-button to the base, a set of contacts adapted to be carried into engagement by the push-button movements of said push-button, means for yieldingly supporting the push-button with said contacts normally disengaged, a second set of contacts having one element thereof connected with the push-button and operated thereby in the rotary movements of such push-button, and means for securing 40 said control switch on the steering column of an automobile. 35

JOHN F. CAVANAGH.
